*Primary Examiner—Prabhakar G. Deshmukh
Attorney, Agent, or Firm—Nixon & Vanderhye P.C.***[57]****CLAIM**

The ornamental design for a “information storage cartridge for game machine”, as shown and described.

DESCRIPTION

FIG. 1 is a right, front, top perspective view of the information storage cartridge for game machine in accordance with a first embodiment of my new design;

FIG. 2 is a left, rear, bottom perspective view thereof;

FIG. 3 is a top plan view thereof;

FIG. 4 is a front elevation view thereof;

FIG. 5 is a rear elevation view thereof;

FIG. 6 is a right side view of the plan shown in FIG. 3, the

left side view being identical thereto; and,

FIG. 7 is a bottom plan view thereof.
